(57) **CLAIM**

The ornamental design for a lumbar interbody spacer implant, as shown and described.

DESCRIPTION

FIG. 1 is a top perspective view of the lumbar interbody spacer implant comprising the new design, showing the tool connector hole and top openings in phantom;

FIG. 2 is a side perspective view of the design of FIG. 1 showing the tool connector hole and the top openings in phantom;

FIG. 3 is a top view of the design of FIG. 1 showing the top openings in phantom;

FIG. 4 is a bottom view of the design of FIG. 1 showing the bottom openings in phantom;

FIG. 5 is a right elevational view of the design of FIG. 1 showing the tool connector hole in phantom;

FIG. 6 is a left elevational view of the design of FIG. 1;

FIG. 7 is a front elevational view of the design of FIG. 1; and,

FIG. 8 is a rear elevational view of the design of FIG. 1 showing the tool connector hole and strut opening in phantom.

The broken lines in the figures are for illustrative purposes only and form no part of the claimed invention.
